UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

WIRE-LINE DRILLING CLAMP.

Application filed February 10, 1926. Serial No. 87,303.

My invention relates to wire-line drilling clamps.

It is the object of this invention to provide a wire line or rope clamp which is simple in construction and capable of operation in both the closing and the opening directions with comparatively little friction. Minor objects pertain to the novel fulcrums and the novel means for holding them in proper relation to each other and the clamping levers.

Referring to the accompanying drawings, Fig. 1 is a side elevation of my improved clamp with a piece of wire line held thereby; Fig. 2, an end elevation, looking at Fig. 1 from the right; Fig. 3, a plan view of the clamp closed and gripping a wire line shown in cross-section; Fig. 4, a plan view of the clamp open; Fig. 5, a section 20 on the line V—V on Fig. 1; Fig. 6, a perspective view of one of the fulcrum blocks; and Fig. 7, a longitudinal section in the plane of the axial center of the pin 26, the levers being broken off.

On the drawing, 1 and 2 designate two clamping levers or members which are substantially alike except that one, as 1, is right handed and the other, as 2, is left handed. The vertical opposed faces 3 and 4 of the levers are provided near one end with opposed vertical grooves containing vertical slips or liners 5 and 6 arcuate in horizontal or cross section, the opposing faces of the liners forming, when the levers are approximately in closed or clamping positions, as shown in Fig. 3, a cylindrical seat for engaging and gripping the wire line 7. The liners are held in place by the bolts 8 passed through the levers and into the liners.

Just beyond the liners 5 and 6 the levers have the opposed horizontal holes 9, and vertically below the holes 9 the opposed horizontal holes 10 parallel with the holes 9. The holes in each lever have their front and rear walls converging outwardly or diverging toward the faces 3 and 4, so that preferably the inner walls of the openings will be approximately in the same vertical plane when the levers are closed, as in Fig. 3, and the outer walls thereof will be approximately in the same vertical plane when the levers are wide open, as in Fig. 4.

Bolts 11 and 12 lie in the respective holes 9 and 10 and extend out beyond the outer

faces of the levers. Vertically above and below each of the holes 9 and 10 in each lever and in the outer faces thereof is a vertical V-shaped notch or groove 13, serving as fulcrums of the levers. The bolts 11 and 12 carry the fulcrum blocks or plates 14 and 15, the former opposite the outer face of the lever 1 and the latter opposite the outer face of the lever 2. The faces of the block 14 and 15 next to the levers have the vertical V-shaped fulcrum ribs or knife-edges 16 seated in the grooves 13. Nuts 17 are screwed on the ends of the bolts and against the outer faces of the fulcrum blocks to secure the levers, blocks and bolts into a mechanical unit, so that, when a wire line 7 is between the liners 5 and 6, and the inner or handle ends of the levers are brought toward each other, the ribs 16 will be fulcrum lines cooperating with the fulcrum grooves 13 to make the levers apply clamping pressure against the wire line. The bolts permit adjustment of the distance between the fulcrum block to compensate for wear of the fulcrums or of the liners or both.

The handle end of one of the levers, as 1, is in the elongated eye of the yoke 18 which is limited in its movement toward gripping end of the lever by the shoulders 19 on the sides of the lever 1, a pin 20 passing through the lever 1 and extending beyond its sides to prevent the yoke from slipping off from the lever, the yoke being between the shoulder 19 and the pin. The eye of the yoke is sufficiently long to be slipped over the handle end of the lever 2 which may have on its outer face the lug 21, in front of which the seat 22 of the yoke rests to prevent the latter from slipping off from the lever 2. The yoke is provided with the screw 23 which is operated by the cross-handle 24 and works with its inner end in the eye of the yoke and against the outer face of the lever 1, to draw the levers 1 and 2 toward each other when the yoke embraces both handle ends, as in Fig. 3 in the operation of clamping the wire line 7 to its seat in the liners.

The upper faces of the levers 1 and 2 are provided above the bolts 11 with the up-standing lugs 25 having holes 32 and 33 in which the pin 26 fits loosely so as not to interfere with the opening and closing movements of the levers 1 and 2. Cotter pins 27 or the like are passed through the pin 26

and are so placed at the outer faces of the lugs as to permit the lever to be closed sufficiently for a wire line gripping operation, as shown in Fig. 3. The pins 27 prevent the loss of the pin 26, the latter causing the two levers to open approximately the same.

By referring to Fig. 7, it is seen that, when the clamp is closed, the side of the pin 26 nearest the liners bears near its center on the opposed inner edges 34 of the holes 32 and 33, and the opposite side of the pin bears near its outer ends on the outer edges 35 of the holes. The opposite edges or portions of the holes bear against the opposite sides of the pins.

If the lever 2 is moved away from the lever 1, it will move for a short angular distance without putting any stress on the pin 26. Soon however the diagonally opposite edges 36 and 37 engage the central outer and extreme inner portions of the pin, and then compel the pin to move concurrently with the lever 2. The inner side of the pin 26 bears against the inner edge 34 of the hole 32 and causes the lever 1 to swing on its fulcrum 16 outwardly away from the lever 2. The pin 26 acts as a lever to force the levers 1 and 2 to open substantially equal angular distances. It is clear that if the lever 1 is moved away from the lever 2, the pin 26 would cause the lever 2 to open substantially the same distance as the lever 1 opens.

Each lever has at its upper side opposite the seats for the wire line 7 an upstanding hook 28 to receive links or reins, as 29, for suspending the clamp on the temper-screw of a well-drilling line. Each hook is closed at the bottom by a sleeve 30 held in place by a bolt 31. The clamp is adapted to grip various objects besides wire lines, such as pump rods, for example.

I claim—

1. In a clamp, a pair of opposed fulcrum blocks, a pair of levers having their outer ends between the blocks and fulcrumed against them, means passed through the blocks and the said ends of the levers for maintaining the blocks a predetermined distance apart, there being gripping surfaces between the said means and the remaining ends of the levers, and means for moving the said remaining ends of the levers, one toward the other.

2. In a clamp, a pair of opposed fulcrum blocks having knife-edge ribs on their opposed faces, a pair of levers having their outer ends between the blocks and ful-

crumed against the ribs, means passed through the blocks and the said ends of the levers for maintaining the blocks a predetermined distance apart, there being gripping surfaces between the said means and the remaining ends of the levers, and means for moving the said remaining ends of the levers, one toward the other.

3. In a clamp, a pair of opposed fulcrum blocks, a pair of levers having their outer ends between the blocks and fulcrumed against them, a bolt passed through the blocks and the said ends of the levers for maintaining the blocks a predetermined distance apart, there being gripping surfaces between the said means and the remaining ends of the levers, and means for moving the said remaining ends of the levers, one toward the other.

4. In a clamp, a pair of opposed fulcrum blocks having knife-edge ribs on their opposed faces, a pair of levers having their outer ends between the blocks and fulcrumed against the ribs, bolts passed through the blocks and the said ends of the levers for maintaining the blocks a predetermined distance apart, the bolts being parallel and including the plane connecting the said ribs and there being gripping surfaces between the said means and the remaining ends of the levers, and means for moving the said remaining ends of the levers, one toward the other.

5. In a clamp, a pair of levers hinged together and a single means loosely carried by both the levers whereby the swinging of one lever away from the other, causes the latter to swing away from the former.

6. In a clamp, a pair of levers hinged together, a common lever carried by the first levers, and bearing points carried by the hinged levers and engaged by the common lever to cause one hinged lever to swing outwardly when the other hinged lever is swung outwardly.

7. In a clamp, a pair of levers hinged together there being in the levers aligned holes, and a cross-pin loosely seated in the holes, the size of the pin and holes being such that when one lever is swung outwardly it carries the pin with it, the pin engaging a wall of the hole in the remaining lever and forcing the latter to swing outwardly.

In testimony whereof, I hereunto affix my signature.

CLYDE S. WRIGHT.
